UNITED STATES PATENT OFFICE.

CARL ALBERT HIRTH, OF STUTTGART, GERMANY.

NAIL-BRUSH.

1,374,851.

Specification of Letters Patent. Patented Apr. 12, 1921.

Application filed September 19, 1917. Serial No. 192,205.

To all whom it may concern:

Be it known that I, CARL ALBERT HIRTH, of 15 Waldeckstrasse, Stuttgart, in the Kingdom of Wurttemberg, German Empire, 5 civil engineer, have invented certain new and useful Improvements in Nail-Brushes, of which the following is a specification.

My invention relates to nail-brushes and has for its object an improved brush of this 10 kind allowing to provide an easier and better cleaning of the finger-nails.

With nail-brushes of the usual kind it is rather difficult to make the bristles enter into the space inclosed between the nails and 15 the tips of the fingers, and further to guide the brush in the proper manner during the operation of brushing.

In the brush according to the present invention these drawbacks have been overcome 20 by providing the brush with a suitable guide surface without however rendering its manufacture more difficult and expensive than has been hitherto the case.

With these objects in view my invention 25 substantially consists in a nail-brush having the bundles of bristles arranged substantially in a circle along the inner wall or walls of a hollow body of circular section presenting a substantially concave guide 30 face to the finger-nails during the brushing operation.

In the drawings accompanying this specification and forming part thereof two forms 35 of a nail-brush embodying my invention are shown,

Figure 1 is a vertical cross-section of the preferred form of my invention,

Fig. 2 a plan of the same, and

Fig. 3 is a vertical cross-section of another 40 form of the invention.

Referring to Figs. 1 and 2 of the drawings ⁴⁵ *c* is the body of the brush proper, of annular shape and provided adjacent its outer as well as its inner circumference with a separate circular row of holes, *e* and *f* respectively, the holes *e* being arranged near the outer circumference, the holes *f* near the inner circumference and the two rows of holes opening toward different faces of the ring *c*. Bundles of bristles *a* and *b* are 50 fixed in the holes *e* and *f* respectively, and in consequence thereof a row of such bundles extends along near the outer annular edge on one side and another row along 55 near the inner annular edge on the other side. *d* is a sleeve shaped body provided

with an annular shoulder *i* on its inner wall so as to present two substantially cylindrical borings *o*, *p* of different diameter. The boring *o* of larger diameter receives the ring *c*, 60 the shoulder *i* serving as a seat. The difference between the diameters of *o* and *p* being about one half of the thickness of ring *c*, the rows of bundles *a* and *b* are separated from the walls *g* and *h* respectively of 65 their borings by an equal distance, said walls serving as guide surfaces for the backs of the finger-nails while the brush is being used.

In order to clean the nails by aid of the 70 said brush, the finger-tips are inserted in either one or the other boring *o*, *p*, and are pressed with their backs against the respective guide surface *g* or *h*. By turning the sleeve *d* together with ring *c* firmly seated in 75 it about its axis, the bundles of bristles *a* or *b* are brought in contact with the finger-tips and are caused to enter the space between the tips and the nails, one after the other, in rapid succession. It is clear that 80 this can be effected quite mechanically and without looking at the brush and fingers, and nevertheless these latter are firmly guided and held in position in front of the bristles by aid of the surface *g* or *h*. 85

Instead of providing the brush with two rows of bristles, one on each face, as shown and described, a single annular row surrounded by a simple guide ring may be provided. However the arrangement shown 90 in the drawings presents the advantage of allowing to treat hands of considerably different size and nails having different curvatures.

Instead of arranging a plurality of rows 95 of bristles on opposite sides of a ring, a sleeve presenting two shoulders of different diameter may be used, a row of bristles being arranged on each shoulder and all the rows extending in the same direction. One 100 form of a brush arranged in this manner is illustrated in Fig. 3. In this figure *d* designates the sleeve, having the shoulders *k* and *m*, on which are seated the annular brush bodies *s* and *t* respectively carrying the rows 105 of bristles *u* and *v*. However the rows of bristles arranged as shown and described lend themselves better for cleaning.

I claim:

1. In a nail brush, in combination, a body 110 provided with a passage therethrough, a plurality of substantially annular rows of

- bristles disposed on said body, and a sleeve-like casing open at both ends surrounding said rows and forming a guide face about each row.
5. 2. In a nail brush, in combination, a ring-like brush body, a sleeve-like casing open at both ends and provided in the interior with a shoulder serving as a seat for said body, said casing being of a different interior diameter on opposite sides of said shoulder, and substantially annular rows of bristles disposed on opposite sides of said body and substantially conforming to the inner circumference of the adjacent portion of the casing.
10. 3. In a nail-brush in combination, a brush body having a passage therethrough, a sleeve-shaped casing, a shoulder within said casing adapted to serve as a seat for said
15. body and substantially annular rows of 20 bristles disposed on opposite faces of said body adjacent to the inner wall of said casing.
4. In a nail brush, in combination, a sleeve-like casing open at both ends and provided with an interior shoulder, a brush body having a passage therethrough disposed on said shoulder, and a substantially annular row of bristles disposed on said body and substantially conforming to the 25 30 inner circumference of the adjacent portion of the casing.

In testimony whereof I affix my signature, in presence of two witnesses.

CARL ALBERT HIRTH.
